UNITED STATES PATENT OFFICE.

CHARLES ALBERT LEE, OF HERKIMER, NEW YORK.

TYPE-WRITER CABINET AND COPY-HOLDER.

SPECIFICATION forming part of Letters Patent No. 398,738, dated February 26, 1889.

Application filed September 10, 1887. Serial No. 249,305. (No model.)

To all whom it may concern:

Be it known that I, CHARLES ALBERT LEE, of Herkimer, in the county of Herkimer and State of New York, have invented certain new and useful Improvements in Type-Writer Cabinets and Copy-Holders; and I do hereby declare that the following is a full, clear, and exact description of the invention, which will enable others skilled in the art to which it applies to make and use the same, reference being had to the accompanying drawings, and to the letters of reference marked thereon, which form part of this specification.

My invention relates to an improvement in type-writing cabinets and copy-holders; and it consists of the mechanism hereinafter described and claimed.

In the drawings like figures of reference refer to like parts in the several figures.

Figure 1 shows my improved cabinet closed and in readiness to be moved or carried. Fig. 2 is a front elevation of the same open and ready for use. Fig. 3 is a side elevation of Fig. 2 with a side wall of the cabinet removed. Fig. 4 is a plan view with a door open. Figs. 5, 6, 7, and 8 show details of construction. Fig. 9 shows a view of a portion of the device, as shown in Fig. 3, on a larger scale. Fig. 10 shows a top view of the door and type-writer mounted thereon, and is especially intended to show the mechanism for securing the type-writer 2 and adjusting it upon the door. Fig. 11 shows a vertical cross-section of a portion of the swinging paper-holder and the roller, being an enlarged view of the same part shown in Fig. 8.

The cabinet *a* consists, essentially, of a box having five stationary walls and a door hinged at the bottom, the type-writer being applied to the door in the manner hereinafter described.

1, Fig. 1, is the door of the cabinet; and 1, Fig. 2, shows the same in the position it assumes when open. The door is connected to the cabinet at the bottom, so as to open outward and downward by hinges or equivalent devices.

2, Fig. 3, is the type-writer in position for use upon the door of the cabinet and attached thereto by the guide 3, in which it is free to move, the same being held in position to be moved reciprocally between the guides by flanges 4, Fig. 2, on the type-writer frame fitting in the rabbeted surfaces of the guides.

By this construction the type-writer may be adjusted toward or from the operator, and when so adjusted held in position.

On one side of the frame of the type-writer I provide ratchet-teeth 5, Figs. 4 and 10, and catch or pin 6, attached to or passing through the guides 4, adapted to engage the ratchet-teeth 5, which catch is operated by spring 7, the spring operating to hold the catch in contact with the ratchet-teeth. The purpose of this mechanism is to provide means for adjusting the type-writer upon the door of the case, and when adjusted to hold the same in fixed relation to the door, as before mentioned.

8, Figs. 3 and 4, show a stop adapted to limit the backward movement of the type-writer 2 within the guides 3 when the cabinet is open, and the downward movement of the same when the door is closed and made to assume a vertical position.

In Figs. 3 and 9 is shown my pivoted paper-holding device, in which 9 is the board or back against which the copy is held. Board 9 is pivoted between opposing walls of the cabinet at 10, Figs. 3, 5, and 9, in such manner as to partially rotate on the pivotal bearings. Rigidly connected to the board 9 in the rear of the pivotal point is an arm, 11, forming a crank-arm. This arm is connected with stud or post 12 on the door of the case by connecting-rod 13, the connecting-rod having swiveled nut 14, Fig. 2, by means of which the connecting-rod may be adjusted. The purpose of this mechanism is to hold the paper-moving device backward and upward from the position shown in Fig. 3 when the door is closed, and to move the same into the position shown in Figs. 3 and 9 when the door is open.

For holding the paper on the board 9 and moving the same to accommodate the operator, I provide pivoted roller 15, Figs. 2, 3, 7, 8, 9, and 11, mounted horizontally on board 9 in or behind opening 16 in the face of board 9, Figs. 8 and 11. The roller is adapted to receive and retain the end of a sheet of paper by means of bar 17, Fig. 7. Bar 17 is held to the roller by being attached to the free end of spring 18, Figs. 7, 8, and 11, which springs are held to the roller 15 by pins or screws at 19, Figs. 8 and 11. The paper being inserted under bar 17 is held on the front of the board 9, as shown at 20, Figs. 8 and 11.

For winding the paper on roller 15, I attach

ratchet-wheel 21, Fig. 5, to the right-hand end of roller 15, with which it is rigidly connected. This ratchet-wheel is engaged by movable rack 22, provided with teeth at one end for engaging the ratchet-wheel and rotating the roller. The rack has a vertical movement, the same being provided with slots 23 23, through which slots headed pins or screws 24 24 pass, attaching it loosely and movably to the inner wall of the cabinet, a slight horizontal movement being allowed at the top to accommodate its movement on the ratchet-wheel. The rack 22 is made to engage ratchet-wheel 21 and to be moved downward by spring 25, attached to the inner wall of cabinet at 26. The rack is moved vertically by rule-jointed lever 27, the lever being jointed outside of the case, as shown at 28, Figs. 3 and 4. The lever is pivoted substantially at its center, so that the operator by pressing downward on the end 29, Fig. 4, thereof, thereby raises the rack and partially rotates roller 15, which winds the paper on the roller one or more lines. This operation may be repeated until the entire sheet of copy is wrapped on the roller. By the operation of the mechanism heretofore described the line from which the operator is copying may always be kept in a uniform position.

For keeping the lower end of the copy-paper in position on the board and guiding the eye in copying therefrom, I provide adjustable bar 30, Figs. 2 and 3. Bar 30 is mounted on arms 31, Figs. 2 and 6, which arms are pivoted in ears 32 on either side of the board at a short distance from the lower end. Bar 30 is made to press against boards 9 by springs 33, Fig. 6, under the end of each arm, and the bar and arms may be moved outward from the board to receive the copy-paper, as shown in dotted lines in Fig. 6. Bar 30 may be adjustable on the arms 31 by being fitted thereto so as to maintain its position when adjusted.

The operation of my device is substantially as follows: The case being closed, as shown in Fig. 1, on opening it the door is brought into the position shown in Figs. 2, 3, and 4. When the door is open, the type-writer 2 will be found in contact with stop 8. It may then be brought forward and secured in position on the door by ratchet-teeth 5 and catch-pin 6. As the door is open, the swinging copy-holder, which, while the case was closed, had been swung to the top of the case, substantially parallel with the top thereof, is brought down by connecting-rod 13 and crank-arm 11 into the position shown in Figs. 8 and 9, in which position it is held while the door is open; also, at the same time that the door is opened the rule-joint 28 of lever 27 straightens out, keeping the end of lever 27 in position to move the rack or bar 22. As the copy-holder swings into the position shown in Figs. 3 and 9, the ratchet-teeth of the roller 15 are brought into contact with rack 22, and the rack is held in engagement

with ratchet-wheel of roller 15 by spring 25. The copy-holding roller 15 may then be operated by lever 27, and be rotated, and the copy-paper, the end of which is clamped between bar 17 and roller 15, rolled upon the roller. In placing the copy in the copy-holder, after the end has been secured on the roller the bar 30 is brought out from the face of the board and the copy placed between the board and the bar, where it is held not very tightly, and so that it will slide under the bar when the roller 15 is rotated by action of spring 32. When it is desired to remove the copy from the copy-holder, the rack 22 is thrown out of engagement with the ratchet-pinion 21 on the end of roller 15, and by drawing on the lower end of the copy it will unroll and slip from between the roller and clamping-bar. In closing the case the type-writer is placed against stop 8, and the door is closed, the copy-holder swinging into the top of the case, as before described.

What I claim as new, and desire to secure by Letters Patent, is—

1. A type-writer case having a swinging door and a type-writer mounted thereon, in combination with a swinging board journaled in the case having a bar mounted on the free ends of arms pivoted to the board and springs for holding the bar adjustably to the face of the board, a roller pivoted to the board having a clamping-bar held to the roller by a spring and adapted to receive the end of a copy-paper between the roller and bar, the crank-arm attached to the board, and a rod connecting the crank-arm and the door, substantially as set forth.

2. A type-writer case having a swinging door and a type-writer adjustably mounted thereon, in combination with a swinging board journaled in the top of the case having a bar mounted on the free ends of arms pivoted to the board and springs for holding the bar adjustably to the face of the board, a roller pivoted in the board having a clamping-bar held to the roller by springs for clamping the copy-paper and rolling it upon the roller, a ratchet-wheel on the roller, a movable rack engaging the ratchet-wheel, and a rule-jointed lever pivoted to the swinging door for operating the rack, substantially as set forth.

3. A type-writer case having a swinging door and a type-writer adjustably mounted thereon, in combination with a paper-holding device consisting of a swinging board journaled in the case, a device for holding the paper to the board, the crank-arm, and the connecting-rod connecting the crank-arm and the swinging door.

In witness whereof I have affixed my signature in presence of two witnesses.

CHARLES ALBERT LEE.
